UNITED STATES PATENT OFFICE.

AVERY H. THOMAS, OF HOUSTON, TEXAS.

PIPE ELEVATOR.

1,407,236.

Specification of Letters Patent. Patented Feb. 21, 1922.

Application filed February 5, 1921. Serial No. 442,626.

To all whom it may concern:

Be it known that I, AVERY H. THOMAS, a citizen of the United States, residing at Houston, Harris County, Texas, have invented a certain new and useful Improvement 5 in Pipe Elevators, of which the following is a full, clear, and exact description, such as will enable others skilled in the art to which it appertains to make and use the same.

My invention relates to an improvement in elevators for use on drilling rigs, for raising and lowering pipe in well drilling. It has particular reference to the clamping 15 block which is locked about the pipe to be handled.

An object of my invention is to provide an elevator block with a latch therefor that may be easily unlatched and raised out of 20 the way of the pipe and which will automatically maintain itself in that position until it is desired to again close the latch. It is also the object of the invention that the latch be constructed to drop to closed 25 position when released and that it be released in the act of pulling on the handle to draw the block against the pipe.

Another object is to form an elevator block which will be strong in construction, 30 which will lock positively when released, and which can be opened conveniently and expeditiously.

Referring to the drawings forming a part 35 hereof and wherein like numerals of reference are applied to like parts throughout the several views, Fig. 1 is a perspective view of my improved elevator block with the bail removed; Fig. 2 is a top plan view on a reduced scale showing the latch withdrawn 40 ready for raising same; Fig. 3 is a similar view showing the latch in locked position and Fig. 4 is a front elevation showing the block in closed position about a piece of pipe, and with the upper part of the supporting 45 bail broken off.

With particular reference to Fig. 1, wherein the form of my improvement is best seen, the block 1 is disclosed as an oblong block somewhat rectangular in form. 50 It is provided with two end trunnions 2 for support by a bail 3 shown broken off in Fig. 4. The block has a central curved recess 4 to receive the pipe to be gripped, the forward face of the recess 4 being beveled outwardly at 5 to permit the pipe to be more readily moved into position therein.

The said recess is closed by a latch 6 which comprises a flat bar pivoted at one end on a pin 7 rotatable in the block as will be described. The rear face of the bar constituting the latch has an extension formed flush with the upper edge of the bar and of about half the vertical thickness of said bar, said extension being curved at 8, on the side toward the recess, to fit about the pipe and thereby serve to hold the same securely. The side of the extension opposite the curved face 8 is perpendicular to the face of the bar itself and acts, when the bar is raised as shown in Fig. 1, to contact with the upper face of the block and to act to help support the latch in proper raised position.

Two forwardly extending brackets 9, 9' serve to retain the latch in proper position and act as a support therefor. The latch, 75 as shown, is of narrow width but obviously may be of such width as desired within limits as set by the size of the elevator. The latch fits, at its outer end, in a recess or notch 10 shaped to receive it and deep 80 enough to admit the full width of the latch.

The manner in which the latch is locked is an important feature of my invention. The outer face of the supporting bracket 9 is 85 provided with two grooves, a vertical one 11 and a horizontal one 11', cut therein at right angles to each other and cutting each other at the central point of the opening through which the pin 7 passes.

The pin 7 is fixed by a set screw 16 at its forward end in a locking block 12 at a point somewhat above the center thereof. As shown particularly in Figs. 2 and 3 said pin passes through the bracket 9, the latch 95 6, and the block 1. The rear side of the block 1 is counter-bored at 13 for a short distance to provide a space, about the pin 7, to receive a spiral spring 14 which bears at one end on the inner wall of the recess 100 and, at its outer end, on the head 15 of the pin. The head 15 is of such size as to loosely fit the counter-bored portion 13. The outer end of the head 15 has a lateral flange 16 to limit its movement into said recess 13.

The locking block 12 has a tongue 17 formed on its inner face and shaped and positioned to fit in either of said grooves 11 or 11', according with the position of the latch. On the side of said locking block toward the pipe recess 4 is a laterally extending rod forming a handle 18 having its

outer end incurved at 19 to fit slidably within a recess 20, formed within a lug 21 projecting from the outer face of the latch.

The operation of my invention will now be understood. When in closed position, as shown in Figs. 1 and 3, the tongue 17 will fit within the vertical groove 11 and will be held resiliently therein by the tension of the spring 14. By grasping the handle 18 and pulling outwardly thereon the operator will move the locking block 12 outwardly to release the tongue 17 from the groove 11 as shown in Fig. 2. The flange 16 on the head of the pin 7 will prevent the movement of the pin beyond the proper distance to release the latch—and the curved end 19 of the handle will not be withdrawn from its recess in lug 21. The operator then throws the latch upwardly to the vertical position shown in Fig. 1. By releasing the handle 18 the operator allows the spring 14 to snap the tongue 17 into the horizontal groove 11', thereby retaining the latch erect out of the way of the pipe until it is again desired to close the same about the pipe. When the block is drawn up against the pipe in position to be clamped about it, the operator pulls on the handle 18 thereby releasing the tongue 17 from the groove 11'. If the pipe is then in position in the recess 4, the operator pushes the latch into closed position. As will be noted, the latch in open position, is pivoted off center, the weight of the latch being greater on the side toward the center of the block. It will therefore drop to closed position and automatically lock itself there without further effort by the operator.

This construction has certain obvious advantages; it can be unlatched by simply grasping the handle and pulling it toward the operator. The latch is automatically locked in inoperative position by simply releasing the handle when the latch is erect. It will be locked when the block is drawn against the pipe and the handle 18 released and dropped. It is simple and strong in construction and will not easily get out of order. While I have shown the preferred embodiment of my invention, it is obvious that various changes in details of construction may be made without departing from the spirit of my invention.

What I claim as new and desire to protect by Letters Patent is:

1. In a device of the character described, an elevator block having a pipe receiving recess, a vertically swinging latch for closing said recess, a pivot pin therefor, a locking block on said pin having a tongue thereon adapted to fit in a groove on said elevator block, said block having approximately vertical and horizontal grooves to cooperate with said tongue, a handle to withdraw said tongue from either of said grooves, and

means on said pin to draw said tongue toward said grooves, when said handle is released.

2. In a pipe elevator, an elevator block having a pipe receiving recess therein, a latch to close the said recess, a pivot for said latch comprising a pin longitudinally slideable in said block and said latch, a locking block on said pin, and co-operating means on said elevator block and said locking block to retain said latch in open or closed position.

3. In a pipe elevator, an elevator block having a pipe receiving recess therein, a latch to close said recess, a pivot pin for said latch comprising a pin slideable in said block, a locking block on said pin, a tongue on said locking block and grooves on said elevator block into which said tongue is adapted to fit to retain said latch in either open or closed position.

4. In a pipe elevator, an elevator block having a pipe receiving recess therein, a latch to close said recess, a pivot pin for said latch comprising a pin slideable in said block, a locking block on said pin, a tongue on said locking block, said elevator block having grooves to co-operate with said tongue, and resilient means to retain said tongue in said grooves.

5. In a pipe elevator, an elevator block having a pipe receiving recess therein, a latch to close said recess, a pivot pin for said latch slideable in said elevator block, locking means on said pin adapted to lock said latch in open or closed position, and a means to retain said locking means resiliently in locking position.

6. In a pipe elevator, an elevator block having a pipe receiving recess therein, a latch to close said recess, a pivot pin for said latch, grooves on said elevator block, a locking block on said pin having a tongue thereon, adapted to fit in the said grooves in said elevator block and a spring on said pin acting to draw said tongue into said grooves for the purpose described.

7. In a pipe elevator, an elevator block having a pipe receiving recess therein, a latch to close said recess, a pivot pin for said latch longitudinally slideable in said elevator block and said latch, and a locking block on said pin, said locking block being held resiliently toward said elevator block and interfitting therewith when said latch is in either open or closed position.

8. In a pipe elevator, an elevator block having a pipe receiving recess therein, a latch to close said recess, a pivot pin for said latch, grooves on said elevator block, a locking block on said pin having a tongue thereon adapted to fit in the said grooves in said elevator block and a spring on said pin acting to draw said tongue into said grooves for the purpose described, and a handle for

said latch by means of which said locking block may be disengaged from said elevator block and said latch be swung on its pivot.

9. In a pipe elevator, a pipe receiving block, a latch thereon, a pivot pin for said latch, a locking block on said pin, co-operating tongue and groove locking means on said locking block and said elevator block, a handle on said locking block having connection with said latch whereby said latch may be unlocked and swung on its pivot in the manner described.

10. In a pipe elevator, a pipe receiving block, a latch therefor, a pivot pin for said latch, a locking block for said pin, a handle

for said locking block and engaging said latch whereby said locking block may be operated to release said latch and said latch may be swung on its pivot.

11. In a pipe elevator, a pipe receiving block, a latch therefor pivoted at one side thereof to swing in an approximately vertical plane and a locking means for said latch adapted to serve as a handle for said latch and to be released when said handle is operated.

In testimony whereof, I hereunto affix my signature, this the 21st day of December, A. D., 1920.

AVERY H. THOMAS.
